UNITED STATES PATENT OFFICE.

DANIEL HILLEMAN, OF ST. LOUIS, MISSOURI.

COALING DEVICE.

1,183,141.

Specification of Letters Patent. Patented Mar. 23, 1915.

Application filed April 7, 1914. Serial No. 830,275.

To all whom it may concern:

Be it known that I, DANIEL HILLEMAN, a citizen of the United States, residing at Wellston, St. Louis, State of Missouri, have 5 invented new and useful Improvements in Coaling Devices, of which the following is a specification.

This invention relates to an apparatus particularly designed for delivering coal to 10 the tenders of traveling trains, the invention comprehending specifically a structure by which the coal is automatically delivered to the tender in the travel of the latter beneath the bins.

15 This invention is an improvement on the coaling devices described and claimed in Letters Patent of the United States No. 1,097,434, granted to me May 19, 1914, the object of the present invention being to provide 20 an improved means for automatically controlling the coal car lever and prevent coal from being casually delivered to said car.

The invention in its preferred form of 25 details will be described in the following specification, reference being had particularly to the accompanying drawings, in which:—

Figure 1 is a plan of the improved coal 30 delivering apparatus. Fig. 2 is a side elevation of the same with the dumping sections locked in position to form a bottom for the bin. Fig. 3 is a similar view with one of the locking slides in released position and 35 the dumping sections in discharge position. Fig. 4 is a side elevation illustrating the relation of the coal delivery apparatus to the track, and showing means for operating the slide. Fig. 5 is a transverse section on the 40 line 5—5 of Fig. 1. Fig. 6 is a longitudinal section on the line 6—6 of Fig. 1.

Referring particularly to the accompanying drawings, the improved delivery apparatus comprises a series of bins 1 including 45 side and end walls 2 and 3, the bins being supported on a platform 4 arranged above the track 5 on a suitable framework 6.

The bins are arranged in longitudinal alinement and are each wholly independent, 50 being preferably provided in series as shown, in order that a number of trains may receive coal therefrom without the necessity of recharging the bin. The bottom of each bin is made up of a plurality, preferably two, dumping sections 7, each having a length approximately one-half the length of

the bin and a width corresponding to the distance between the side walls of the bin. Each dumping section is pivotally mounted between side walls of the bin on a shaft 8, 60 said shaft being secured to the section adjacent one end thereof, as shown. The shafts are preferably arranged adjacent similar ends of the dumping sections, that is the shaft of one dumping section will be secured thereto adjacent the end wall 3 of the bin 65 while the shaft of the remaining dumping section will be secured thereto adjacent the center of the bin. By this construction the dumping sections tilt in the same direction 70 in operation and therefore avoid the possibility of binding under the load. The shorter end of each dumping section is provided with a weight 9 serving to counter-balance the longer end of the section, so that 75 when free to operate, the sections resume a horizontal or bottom forming position. The ends of the shafts 8 project beyond the side wall 2 of the bin, and are provided with locking members 10 rigidly secured to the 80 shaft. Said members are of rectangular form having their major length corresponding and in alinement with the dumping section, and are arranged on the shaft so that they are in spaced relation from the side 85 wall of the bin.

To the side wall of the bin in alinement with the locking members are fixed trackways 11 which trackways include guiding sections 12 secured to the sides 2 by reduced 90 web portions, the guiding sections corresponding in width and height to the similar dimensions of the locking members. A slide is arranged for co-operation with the trackways including a body 13 formed with a 95 longitudinally extending channel 14 of a size to receive and co-operate with the trackways 11, the entrance to said channel through the inner side of the slide snugly fitting the web of the trackway to prevent 100 separation of the slide and trackway. The slide is also preferably provided with anti-friction rollers 15 which bear upon appropriate portions of the track in the movement 105 of the slide, whereby to insure easy movement and avoid undue friction. As the slide and channel are of a size and shape to co-operate with the trackways, it will obviously so co-operate with the locking members 10 when the latter are alined with the trackway. The slide is of a length exceeding the 110 distance between the proximate ends of the

trackways 11, so that the slide is always in coöperation with one or the other trackway. Depending from the slide at each end is a standard 16, which is preferably braced 5 from the body by a brace 17.

The coal car is provided with hand operated levers 18 pivoted on the side thereof and connected to a trip lug 19 mounted in a recess 20 on the inner side of the car, the 10 operation of the lever serving to project the lug above the car and into the path of the standard 16 of the slide, or to withdraw the lug beyond the possibility of coöperation with the standard. In use, the slide bar 15 is moved longitudinally of the trackways until it embraces both of the locking members 10 of the dumping section and by reason of the formation of said members, said slide will hold the dumping sections 20 against movement toward dumping position. As the train approaches, which is to receive a load of coal, the lever 18 thereon is operated to project the trip 19 above the car. As the train advances said trip will 25 engage one of the standards 16 and in the forward travel of the train move the slide lengthwise the trackway and free the locking members 10. The dumping sections, by reason of the load sustained, will immediately 30 move to dumping position and discharge coal into the car, it being understood that the parts are so proportioned that the car moves beneath the dumping sections as the latter are released. By providing a series 35 of bins lengthwise the track it is obvious that a number of trains can receive a load of coal without the necessity of continually recharging a particular bin and furthermore I contemplate any single track structure and arrangement of alternate bins so that they 40 may be operated by trains traveling in opposite directions.

The various parts of the structure are to be constructed of substantial material which 45 will stand the usage to which such devices are ordinarily put, and when so constructed will automatically deliver to a traveling train a load of coal from a particular bin without the necessity of stopping the train 50 or other action by the crew except the adjustment of the lug 19. Any means may be provided for restoring the slide to locking position, such for example, as a cable or rod, it being understood that the dumping sections 55 automatically return to normal position after having discharged their load, by virtue of which the locking members 10 are automatically positioned to receive the slide when it is returned to set or operative position.

In order to control the operation of the lever 18 and thereby prevent a load from being casually and undesirably dumped in the coal car and in order to protect the engineer and fireman from injury by such an 60

occurrence I provide the lever 18 with an outwardly extending tappet roller 21 which is mounted near the free end of said lever. I also provide a cam rail 22 for coacting with said tappet roller and thereby raising 70 said lever immediately after a load has been dumped in the coal car and thus cause the lever to automatically adjust the lug 19. This cam rail is secured on the posts or other suitable supports 23 at a suitable point at 75 one side of the railway track. The cam rail comprises the oppositely inclined upwardly converging end portions 24 and the horizontally arranged elevated, intermediate portion 25. A brace rod 26 is also employed 80 which is arranged a suitable distance below the elevated portion 25 and ends of which are connected to the inclined cam portions 24. Immediately after a load has been dumped into the coal car the forward movement of the train brings the tappet roller 21 into engagement with one of the cam ends 24 of the cam rail thus causing the free end of the lever to be automatically raised and thereby lowering the lug 19 to prevent the 85 operation of other dumping sections; the length of the elevated portion 25 of the cam rail being such as to hold the lever 18 in elevated position until after the coal car has passed from under the elevated bin. 90

Having thus described my invention, I claim:—

1. In combination with coal delivery apparatus comprising a bin above the railway track, a dumping member forming the bottom of the bin and having a locking element, a guide track and a slide mounted for movement on the guide track and to normally engage the locking element to hold the dumping member in closed position; car-carried means to engage and operate the slide, car-carried means to project and withdraw said slide-engaging means and fixed means, at one side of the railway track to automatically withdraw said slide-engaging 100 means as the car passes.

2. In combination with coal delivery apparatus comprising a bin above the railway track, a dumping member forming the bottom of the bin and having a locking element, a guide track and a slide mounted for movement on the guide track and to normally engage the locking element to hold the dumping member in closed position; car-carried means to engage and operate the slide, and including a lever, a tappet on said lever, and a fixed cam rail at one side of the railway track and arranged to engage said tappet and actuate said lever to cause the latter to automatically move the slide-engaging means to inoperative position.

3. In combination with coal delivery apparatus comprising a bin above the railway track, a dumping member forming the bottom of the bin and having a locking element, 110

a guide track and a slide mounted for movement on the guide track and to normally engage the locking element to hold the dumping member in closed position; car-carried
5 means to engage and operate the slide, and including a lever, a tappet on said lever, and a fixed cam rail at one side of the rail-way track and arranged to engage said tappet and actuate said lever to cause the latter
10 to automatically move the slide-engaging

means to inoperative position, said cam rail having an inclined cam member and an elevated supporting member.

In testimony whereof I affix my signature in presence of two witnesses.

DANIEL HILLEMAN.
